UNITED STATES PATENT OFFICE.

JOHN STROTHER THURMAN, OF ST. LOUIS, MISSOURI.

DUST-DISPLAY DEVICE FOR VACUUM CLEANING-TOOLS.

No. 918,932.

Specification of Letters Patent.

Patented April 20, 1909.

Application filed February 18, 1908. Serial No. 416,629.

To all whom it may concern:

Be it known that I, JOHN STROTHER THURMAN, a citizen of the United States, and resident of St. Louis, Missouri, have invented 5 certain new and useful Improvements in Dust-Display Devices for Vacuum Cleaning-Tools, of which the following is a specification containing a full, clear, and exact description, reference being had to the accompanying drawings, forming a part hereof.

My invention relates to a dust display device for vacuum cleaning tools, the object of my invention being to construct a device to be located in the tube or pipe of a cleaning 15 apparatus which conveys the dust from the cleaning tool to the dust tank, and by means of which device the operator is at all times enabled to readily observe the passage of dust through the dust conveying tube of the 20 cleaning apparatus.

To the above purposes, my invention consists in certain novel features of construction and arrangement of parts, which will be hereinafter more fully set forth, pointed out 25 in the claims, and illustrated in the accompanying drawings, in which:—

Figure 1 is a plan view of the dust display device; Fig. 2 is a vertical section taken on the line 2—2 of Fig. 1; Fig. 3 is a trans- 30 verse section taken on the line 3—3 of Fig. 2.

Referring by numerals to the accompanying drawings:—1 designates the base of the device which is preferably formed of cast metal in the shape of a bowl, and provided 35 on its edge with an integral vertically disposed wall 2, the lower edge of which rests upon the floor, thus forming a support for the device.

Formed through opposite sides of the body 40 1 are circular openings 3, through which the dust passes in its travel through the device, and screw seated in said openings are the inner ends of tubes 4, to which the ends of the vacuum hose are attached.

Formed integral with the upper edge of 45 the body 1 is a vertically disposed flange 5, and positioned on top of the body 1, within this flange, is a packing ring 6, of rubber, or analogous material.

7 designates a hollow hemi-spherical mem- 50 ber, of glass, or analogous transparent material, on the lower edge of which is formed a flange 8, which rests upon the ring or gasket 6; and positioned on top of said flange, with- 55 in the flange 5, is a second ring or gasket 9, of rubber, or analogous material.

10 designates a retaining ring, which is positioned on top of the ring or gasket 9, and passing through said ring is a series of screws 11 which are seated in the flange 5, thus 60 rigidly uniting the transparent member 7 with the base 1; and the packing rings or gaskets 6 and 9 engage on both sides of the flange 8 to thoroughly pack the joint between said base and member to prevent the 65 leakage of any air into the device.

It will be noted that the bowl shaped base 1 and the member 7, when united, form a hollow spheroid, the inner surface of which is practically smooth and unbroken; and the 70 inlet and outlet openings 3 in the base of the housing are formed directly opposite one another; and this arrangement readily permits the dust laden air to pass through the entire device without choking, or without breaking 75 its force.

When a cleaning apparatus provided with the dust display device is in operation, the operator by looking through the transparent member 7 can readily observe the amount of 80 dust passing through the dust conveying tube, and by thus noting the cleaning action, can regulate the operation of the cleaning tool of the apparatus.

A device of my improved construction is 85 simple, inexpensive, easily applied to the dust conveying tubes of vacuum cleaning systems; and, when installed, readily permits an observer to see the passage of dust through the apparatus.

I claim:—

1. The combination with the dust conveying tube of a vacuum cleaning apparatus, of a housing, the lower portion of which is bowl shaped and provided with inlet and 95 outlet openings which are arranged directly opposite one another; and a portion of which housing is transparent.

2. The combination with the dust conveying tube of a vacuum cleaning apparatus, 100 of a housing located in the dust conveying tube, the lower portion of which is bowl shaped and provided with inlet and outlet openings which are arranged directly opposite one another; and a transparent cover for 105 said housing.

3. The combination with the dust conveying tube of a vacuum cleaning apparatus, of a housing located in the dust conveying tube, the lower portion of which is bowl 110 shaped and provided with inlet and outlet openings which are arranged directly opposite one another.

site one another; a transparent cover detachably positioned on the housing, and packing rings arranged between the edges of the housing and the transparent cover.

5 4. A dust display device for vacuum cleaning systems, comprising an air tight housing, the lower portion of which housing is bowl shaped, and provided with inlet and outlet openings which are arranged directly opposite one another and a portion of which housing is transparent.

10 5. The herein described dust display device for vacuum cleaning systems, comprising a bowl shaped base in which is formed a 15 pair of oppositely disposed openings, tubular

members seated in the base and communicating with said openings, an inverted bowl-shaped transparent member arranged on the base, flexible packing rings engaging the edges of the transparent member, and a retaining ring fixed to the base and bearing on the upper one of the packing rings. 20

In testimony whereof, I have signed my name to this specification, in presence of two subscribing witnesses.

JOHN STROTHER THURMAN.
